LINER SUPPORT IN HOT-AIR FURNACE

Harry L. Giwosky, Wichita, Kans., assignor to
The Coleman Company, Inc., Wichita, Kans.,
a corporation of Kansas

Application April 13, 1948, Serial No. 20,641

4 Claims. (Cl. 126—114)

1

This invention relates to a heater structure. The invention is particularly useful in floor furnaces and other type of furnaces in which inner casings or liners are employed about heating units, etc.

One of the unsatisfactory features of heating furnaces employing liners or inner casings, etc. about heating units, is that the sheets of metal, when heated and cooled, tend to flex back and forth over center producing a cracking or popping noise. For example, a box-like casing or liner, when heated by the heater unit on its inner side, tends to expand or elongate, and the side walls or end walls thereof produce the cracking noise commonly associated with the flexing of an "oil-can" wall. This "oil-can" effect is irritating and it often gives the impression that the furnace has been damaged or is defective. The problem of providing a furnace or heater with casing walls which do not produce this undesirable effect, has not been solved up to the present time.

An object of the present invention is to provide a heater structure in which the casing or liner sheets are so formed as to prevent the flexing of the sheets over center when caused to expand by temperature increases, etc. Another object is to provide preformed casing or liner structures for heaters or furnaces which, when allowed to expand normally under rising temperatures, will not carry the contour of the sheets past a straight line, thus eliminating the "oil-can" effect. Yet another object is to provide a means for attaching the central portion of liner or casing sheets to permit the free expansion of the sheets in any direction without deforming the other sheets due to a variation in temperature between the sheets. A further object is to provide a casing structure of a preformed or bowed construction, permitting expansion in a manner which tends to straighten the casing while preventing the temperature expansion from carrying the contour of the casing past a straight line. Other specific objects and advantages will appear as the specification proceeds.

The invention is illustrated, in a single embodiment, by the accompanying drawings, in which—

Figure 1 is a top plan view, shown partly in section, of a heater structure embodying my invention; Fig. 2, an end view in elevation, a portion of the apparatus being broken away and shown in vertical section; Fig. 3, a perspective view of the inner casing; Fig. 4, a perspective view of the inner liner; and Fig. 5, an enlarged sec-

2

tional detail view, the section being taken as indicated at line 5—5 of Fig. 1.

In the illustration given, 10 designates an outer casing. 11 designates an inner casing. 12 indicates an inner liner. Upon the top of the casing 10 is a frame member 13, which is preferably equipped with a grill (not shown). The bottom of the casing 10 is equipped with a conduit 14 for supplying oil or other fuel to a heater (not shown) within the casing 10. The products of combustion pass from the heater into the heater casing 15. A central casing 16 receives the products of combustion, and this casing communicates with the radiators 17 on either side thereof through the conduits 18.

The structure so far generally described is that of a floor furnace. Air enters through the openings in the frame member 13 resting on the floor and passes downwardly through a chamber 19, as indicated by arrows in Fig. 2. The air then rises through chamber 20, which lies between the inner liner 12 and the radiator 17. The heated air is discharged through the central opening 21 provided by the inner casing 11 and passes through the central portion of the opening in the frame member 13. The operation of the floor furnace is described in detail in Olds Patent No. 2,086,301, which issued on July 6, 1937.

In the floor type of furnace heretofore employed, as well as in other types of furnaces, considerable difficulty has been experienced with the liner or casing lying adjacent the heating element. In the specific type of structure illustrated, the liner 12, by reason of its juxtaposition to the radiators 17, expands under high temperatures and contracts upon cooling. The sheets, forming the liner 12, tend to flex out of a straight plane under such expansion and contraction and produce the well-known "oil-can" effect.

To overcome the above difficulty, I have provided the inner casing 11 with inwardly-embossed member 22 which form flat webs inwardly of the plane of the casing 11. I also provide the liner 12 with outwardly-embossed members 23 terminating in flat webs abutting the webs 22, as shown more clearly in Figs. 1 and 5. The embossed members or webs 22 and 23 may be connected by a rivet 24, as shown in Fig. 5, or by spot welding or other suitable means.

As shown more clearly in Fig. 1, the inner casing 11 is formed by elongated side walls having end portions clinched with the end portions of sheet and walls. The end wall on one side is supported by a post 25, which is carried by a bracket 26 fixed to the outer casing 10. The opposite

end wall is supported by posts 21 carried by the bracket member 28 fixed to the outer casing 10. The posts 25 and 27 are welded or otherwise permanently anchored to the inner casing 11 and may, if desired, terminate at the liner 12. In the illustration given, however, the posts extend through an enlarged recess (not shown) in the sheets 30 to permit free movement of the sheets 30 relative to the posts 25 and 27. The posts 27 are preferably reduced in diameter where they extend through the sheets 30 so as to permit free play of the sheet 30 relative thereto.

The liner 12 is similarly formed of sheets, the elongated side sheets 29 being secured to end sheets 30. The sheets 29 and 30 are secured together by clinching or interlocking of their end portions, as shown more clearly in Fig. 1. The liner sheets 29 and 30, however, are characterized by the fact that the sheets are bowed outwardly substantially throughout their width, while their end portions are inclined slightly in an inner direction. The purpose of this preformed or bowed effect is to compensate for thermal expansion of the sheets which tends to straighten the sheets. The sheets 29 and 30, when unheated, present the bowed appearance, illustrated in Fig. 1, and when heated, tend to assume a straight line position. The curvature of the sheets is such, however, that under the highest expansion, the sheets never quite reach the straight position and do not carry their contour past a straight line. Thus, there is no cracking or popping noise and the "oil-can" effect is avoided. By supporting the inner liner sheets 29 and 30 along their central portions, there is permitted the free expansion of the sheets in any direction without the probability of deforming one or the other sheets due to a variation in temperature between the sheets.

In addition to giving the sheets 29 and 30 the bowed shape illustrated, I prefer also to form the casing 16 of the central heating unit with slightly bowed side walls 31 and 32, so that, under temperature expansion, these walls will also tend to approach a straight line but will never pass beyond a straight line.

Operation

In the operation of the structure, the heater is operated in the usual manner by the supplying of oil or other fuel through pipe 12 to the heater, and the products of combustion pass upwardly through casing 16, pipes 18, radiator 17 and out through flue outlets 33. Since the operation of the heater is well known, a detailed description is believed to be unnecessary. Air from the room above passes downwardly through the side passages 19 to a point below the liner 12, and then passes upwardly about the heater unit through passage 20. Air is discharged into the room through the central outlet 21 of the inner casing 11. As the temperature rises, the liner sheets 29 and 30 tend to straighten and approach the straight-line position. The curvature of the sheets, however, is such that the straight-line position is not quite reached and is never passed, so that a flexing of the sheets does not occur. Should one of the sheets 29 be heated more than one of the end sheets 30, then free attachment of the sheets at their ends permits one to move farther than the other and without deforming the other, and, in any event, the movement of one sheet never forces the other to a position past a straight line.

The bowing of the sheets may be outwardly, as described, or inwardly as desired, the pre-set

curvature being such that the straight-line position will not be reached.

The invention herein has been described in connection with a floor furnace for the purpose of illustrating the invention. It will be understood that the invention is applicable to any type of heating furnace in which casing members are employed adjacent sources of heat and where the flexing of the casing parts would otherwise produce the "oil-can" effect. It will be understood that in other types of furnaces, the casing in question may be supported directly upon an outer casing or frame and may, if desired, form the casing about any type of heat source.

While, in the foregoing specification, I have set forth a description of one embodiment of the invention in considerable detail for the purpose of illustrating the invention, it will be understood that the details of structure, as well as the arrangement of the casing parts, may be modified widely by those skilled in the art without departing from the spirit of my invention.

I claim:

1. In a heater structure, an outer casing, an inner casing, a heater within said inner casing, a box-shaped liner between said heater and inner casing and comprising side and end sheets secured together at their ends, said sheets being bowed outwardly substantially throughout their width whereby the central portions of said sheets are brought adjacent the inner casing, said inner casing and said sheets being provided with embossed portions extending toward each other at the central portion of the sheet to bring the web portions thereof into engagement, and means for securing said web portions together.

2. In a heater structure, an outer casing, an inner casing, a heater within said inner casing, a box-shaped liner between said heater and inner casing and comprising side and end sheets secured together at their ends, said sheets being bowed outwardly substantially throughout their width to bring the central portions thereof adjacent said inner casing, said sheets at their central portions and the adjacent portions of said inner casing being provided with integral web portions extending toward each other and into contact with each other, the abutting surfaces of said web portions being flat, and means securing said flat web portions together.

3. In a heater structure, an outer casing, an inner casing, a heater within said inner casing, a box-shaped liner between said heater and inner casing and comprising side and end sheets secured together at their ends, said sheets being bowed outwardly substantially throughout their width whereby the central portions of said sheets are brought adjacent the inner casing, said sheets at their central portions and the adjacent portions of said inner casing being provided with integral web portions extending toward and in contact with each other, and means securing said web portions together.

4. In a heater structure, an outer casing, an inner casing suspended from said outer casing, a heater within said inner casing, a box-shaped liner between said heater and inner casing, said liner comprising side and end sheets secured together at their ends, said sheets being bowed outwardly substantially throughout their width to bring the central portions thereof adjacent said inner casing, said sheets at their central portions and the adjacent portions of said inner

5

casing being provided with integral web portions extending toward and abutting each other, means securing the abutting portions of said webs together, and means carried by said inner casing for supporting at least an opposed pair of walls of said inner casing upon said outer casing.

HARRY L. GIWOSKY.
